UNITED STATES PATENT OFFICE.

SYLVESTER EASTMAN, OF PROVIDENCE, RHODE ISLAND, ASSIGNOR TO THE SYNCHRONOUS TIME COMPANY OF PORTLAND, MAINE.

ELECTRIC REGULATOR FOR PENDULUM-CLOCKS.

SPECIFICATION forming part of Letters Patent No. 337,385, dated March 9, 1886.

Application filed June 1, 1885. Serial No. 167,196. (No model.)

To all whom it may concern:

Be it known that I, SYLVESTER EASTMAN, of Providence, county of Providence, and State of Rhode Island, have invented an Improvement in Regulators for Clocks, of which the following description, in connection with the accompanying drawings, is a specification, like letters on the drawings representing like parts.

10 This invention has for its object to provide a pendulum-rod of a clock, or other apparatus employing a pendulum-rod, with a supplemental weight comprising a frame movable with relation to the said rod and supporting-magnets, a pivoted armature, and a regulating device co-operating therewith, whereby when the magnets are energized the said supplemental weight will be raised or lowered to accelerate or retard the oscillations of the

15 pendulum-rod.

The invention consists in the combination, with a pendulum-rod provided with the usual weight or bob, of a supplemental weight mounted loosely upon said pendulum-rod, the supplemental weight comprising a frame and two magnets supported thereby, an armature pivoted thereon, and regulating device co-operating therewith, whereby when the magnets are energized the armature actuates the regulating device, effecting the movement of the entire supplemental weight, raising or lowering it upon the pendulum-rod as occasion may require.

20 The regulating device in this instance consists of an upright mounted upon the armature, and having two spring-controlled pawls, which engage with and turn a gear-wheel on a screw-threaded tube fixed to the pendulum-rod, said gear-wheel being in engagement with the frame, and by its rotation raising and lowering the latter, together with the magnets supported by it. The magnets are connected in circuit with a battery, and are energized to attract the pivoted armature by a suitable

25 circuit-changing device arranged in the same circuit.

Figure 1 shows in top view a supplemental weight and its regulating devices applied to a portion of a pendulum-rod, the usual weight

or bob being omitted; Fig. 2, a longitudinal section taken on the dotted line xx , Fig. 1; Fig. 3, a detail showing the spring-controlled pawls in engagement with the gear-wheel; Fig. 4, a diagram of the magnets and their circuits, and Fig. 5 a detail to be referred to.

55

The pendulum-rod A , of usual construction, may be supplied with any suitable weight or bob at its lower end. A tube, a , of suitable length, surrounds the pendulum-rod A at a point above the usual weight or bob, and is securely fixed thereto by screws 2 or other suitable fastenings. The tube a is screw-threaded at a' for a portion of its length, and is also slotted at opposite sides in the direction of its length, as at a'' , forming guideways for a frame composed, essentially, of two bars, b b , fitted to slide in the said guideways a'' , portions of the bars being turned outward at their lower ends and supporting cross-pieces b' b' , which in turn support cross-pieces b'' b'' , connecting the free ends of the cross-pieces b' b' , the cross-pieces b'' b'' supporting two magnets, m m' . Also, pivoted to the bars b b at opposite sides of the pendulum-rod, is a compound armature, c , which is attracted by the magnets m m' when the latter are energized, projections integral with the armature c and extending from the interior thereof between each other and entering holes in the bars b b , as shown in dotted line, Fig. 1, and section, Fig. 2, serving as pivots. This pivoted armature c co-operates with a regulating device, by which movement is imparted to the frame and its connected parts, which collectively form a supplemental weight, the movement of which upon the pendulum-rod accelerates or retards the oscillation of the latter.

75

25 The regulating device in this instance is constructed as follows: The compound pivoted armature c (best shown in Fig. 1, and of suitable shape to co-operate with the magnets m m') is provided at one side with an upright, c' , (see Fig. 2,) rigidly connected therewith, and said upright has mounted loosely at its upper end two pawls, c'' c'' , extending in opposite directions. The pawls c'' are pressed forward by a weak spring, c^3 , mounted upon the upright c' , to engage with the gear-wheel d ,

80

90

95

having a screw-threaded hub and turning upon the screw-threaded tube a' , and the said pawls are normally held disengaged from the gear-wheel and against the pressure of the spring c^3 5 by pins 10, rigidly secured to any moving part, and herein shown as attached to the magnets, the inner curved faces of the pawls c^2 bearing against the said pins 10, so that as the upright c' is moved by the armature c one of the pawls c^2 , pressed by the weak spring c^3 , is moved 10 around its pin 10, against which it bears, and engages the gear-wheel to retain the latter.

The bars b pass upward in the guideways a^2 through the gear-wheel, and are provided 15 each with projections 3 4, which bear against the opposite faces of the said gear-wheel d , so that as the gear-wheel is rotated upon the screw-threaded tube a' it raises and lowers the bars and the parts supported thereby.

20 The armature c is turned on its pivot by the attraction of one of the magnets m or m' , and is restored to its normal condition by a strong flat spring, 5, attached to a projection, 6, extending from one of the bars (see Fig. 2) by 25 an adjusting-screw, 7, the free ends of the said spring acting against the compound armature c at opposite sides of its pivotal connection. (See Fig. 5.) The spring 5, controlling the armature c , is sufficiently strong to overcome 30 the action of the weak spring c^3 , so that as it returns the armature c to its normal position its connected parts—viz., the upright c' and attached pawls c^2 —are also restored to their normal position, the pawls c^2 moving backward 35 around the pins 10, bearing against the latter, and compressing the weak spring 5. The magnets m m' are in circuit with a battery, B, (see Fig. 4,) and are energized to attract the pivoted armature c by a circuit-changing device consisting in this instance of 40 ordinary press-buttons, 8 8, adapted to close the circuit, which is preferably normally open.

The operation of the apparatus is as follows: When the oscillations of the pendulum-rod are 45 to be accelerated or retarded, one of the circuit-closers 8 is operated, which energizes its corresponding magnet, m or m' , attracting the pivoted armature c , moving the uprights c' , with its connected pawls, in the ear of a circle until one of the pawls, passing over its pin 10 and compressed by the spring c^3 , engages the gear-wheel d , and rotates the same upon the screw-threaded tube a' a distance corresponding to one tooth of the gear-wheel, when the circuit-closer is released by the operator. The pivoted armature c , with its connected upright c' , is then restored to its normal condition by the 55 spring 5, which is sufficiently strong to over-

come the action of the spring c^3 , thus permitting the pawls c^2 to become disengaged from the gear-wheel and restored to their normal position, guided by the pins 10, which bear against their inner grooved faces. As the gear-wheel d is thus rotated, it raises or lowers the bars, with their supporting-magnets, to accelerate or retard the oscillation of the pendulum-rod. The slots a^2 are of sufficient length to permit the adequate movement desired.

It is obvious that the screw-threaded tube a may be dispensed with, the screw-thread being formed directly upon the pendulum-rod, and suitable guideways, a^2 , formed therein to permit the bars b to slide freely.

I claim—

1. A pendulum-rod and a movable frame 75 thereon, and magnets and a pivoted armature mounted on the said frame, and means controlled by the said armature to effect the sliding of the said frame upon the pendulum-rod, combined with an electric circuit containing 80 circuit-changing devices, whereby the armature is positively moved, substantially as described.

2. The pendulum-rod and screw-threaded tube thereon, combined with a movable weight 85 consisting of a frame, the magnets and pivoted armature, and regulating device supported by the frame, substantially as described.

3. The threaded pendulum-rod having guideways, combined with a supplemental 90 weight moving vertically therein and comprising a frame, magnets, a pivoted armature, and a regulating device, substantially as described.

4. The pendulum-rod and screw-threaded tube thereon, having guideways, and frame 95 moving on the said rod, combined with two magnets supported by the said frame, the pivoted armature and gear-wheel d , and means to rotate the latter, substantially as described.

5. The pendulum-rod and screw-threaded tube thereon having guideways, the frame movable thereon, and magnets, combined with a pivoted armature co-operating with the said magnets, spring-controlled pawls connected with and operated by the said armature, and a gear-wheel rotated upon the screw-threaded tube by the engagement of the pawls, substantially as described.

In testimony whereof I have signed my name to this specification in the presence of two 110 subscribing witnesses.

SYLVESTER EASTMAN.
